UNITED STATES PATENT OFFICE

JOHN A. MILLER, OF HOMEWOOD, ILLINOIS

BRAKE STRUCTURE

Application filed May 10, 1928. Serial No. 276,606.

My invention relates to brake structure designed particularly for use in connection with pleasure railways and operable from a distance to gradually check the speed where necessary and for smoothly and gradually bringing cars to a stop at the end of a trip without jarring or other inconvenience to the passengers, and without undue strains upon the cars or track structure.

An important feature of the invention is the provision of eccentric pressure units for forcing together two brake beams between which brake shoes on the cars are adapted to pass. Other features of the invention involve improved construction, arrangement and adjustability.

The various features are incorporated in the structure shown on the accompanying drawings, in which

Fig. 1 is a plan view of a portion of track showing my brake structure mounted thereon.

Fig. 2 is an enlarged section on line 2—2 Fig. 1, and showing a car, in rear elevation, on the track.

Fig. 3 is a plan view of one eccentric unit and the brake beams, in open position, associated therewith.

Fig. 4 is a similar plan view showing the unit in operation to shift the brake beams toward each other into braking position, and

Fig. 5 is a section on plane 5—5 Fig. 4.

The brake structure is mounted on the road bed of the railway in the path of the cars. I have shown ties 10 supporting the rail timbers 11 on which are the rails 12 for the wheels 13 of cars C. The brake structure comprises a brake beam 14 which is rigidly secured to the ties as by bolts 15, the beam being set on edge and extending parallel with the rails and having secured thereto along its inner face at the top thereof a metal brake or friction strip 16.

A beam 17 rests flat on the ties alongside of but spaced away from the stationary brake beam 14 and serves as a support for the movable brake beam 18 which is mounted thereon to be opposite the beam 14. The beam 18 has secured thereto the metal brake or friction strip 19 and between these brake strips

passes the brake fin or shoe 20 secured to and depending from the cars which travel on the track. The brake shoe may be the vertical flange of a length of angle bar secured by its horizontal flange to the car as shown.

For controlling the braking pressure of the brake strips against the brake shoe I employ a plurality of eccentrically operated units operable from a distance to powerfully force the brake beam 18 toward the brake beam 14. Each unit comprises a base 21 secured by bolts 22 to the supporting beam 17. Bearing on top of each base is a cylindrical block or disk 23 to which is secured, eccentric thereof, a shaft 24 which extends downwardly through and bears in the base. An eccentric strap or frame 25 receives the eccentric disk and has lugs 26 whereby it is secured to the movable brake beam 18. The shaft also extends through the supporting beam 17 and at its lower end has secured thereto an operating lever 27.

The supporting beam for the eccentric units is not secured to the ties but is adjustably anchored to the stationary brake beam 14 by bolts 28. These bolts take up the strain of the braking pressure and by means of them the gap between the brake strips can be readily and accurately adjusted.

The levers of the various eccentric units are connected at their outer ends to a common operating rod 29 upon which a powerful pull can be exerted by suitable hand or power operated means (not shown), and such means can be at some distance from the brake structure so that cars can be safely braked and retarded or stopped as desired. As shown, the operating rod may be in the form of piping having fittings 30 from which extends pins 31 for receiving the lever ends. The eccentric units are preferably positioned between ties and the piping is supported by and slides on the ties.

In Figs. 1 and 3 the brake structure is shown in open position ready to receive the brake shoe of an approaching car, and to permit ready entrance of the shoe, the ends 14' and 18' of the brake beams are flared as clearly shown in Fig. 1. As soon as the brake shoe has entered the braking gap, the operator

exerts pull on the rod 29 to swing the levers and thereby rotate the eccentric disks in their frames 25 with the result that the movable brake beam 18 is powerfully forced toward the stationary brake beam and the car brake shoe is clamped or squeezed between the braking or friction strips 16 and 19 and the motion of the car can be checked to the degree desired depending upon the braking pressure exerted. The brake structure could also be set for any desired braking action before it is engaged by a car, the flared or rounded ends of the brake beams permitting the car brake shoe to readily enter between the beams. Figs. 2, 4 and 5 show the brake structure in braking position, the eccentric disks having forced the movable beam 18 along the supporting beam 17 and toward the stationary beam 14 to squeeze the brake shoe. To bodily set the eccentric units relative to the stationary brake beam, or to compensate for wear of the brake strips or shoes, the nuts 28' of the bolts 28 are properly turned until the desired adjustment or condition is obtained.

As shown in Fig. 2 the safety rollers 32, which cooperate with the safety rails 33 to keep the car to the rails, will serve also to keep the brake shoe in alignment to properly enter the brake structure.

The throw of the movable brake beam from open to braking position is comparatively small and by virtue of the eccentric units and their long operating levers it requires only a light pull on the operating rod to effect powerful braking and such braking can be smooth and gradual without jarring or inconvenience to the passengers or undue strain on the cars or brake structure.

I do not desire to be limited to the exact construction and operation shown as modifications are possible without departing from the spirit of the invention.

I claim as follows:

1. In brake structure of the class described the combination of a stationary brake beam, a movable brake beam, a plurality of stationary bearing bases alongside of said movable beam, a cylindrical cam disk on each base and a shaft extending eccentrically therefrom through the base, a cylindrical bearing frame receiving each disk and secured to said movable beam, a lever extending from each shaft, and an actuating rod connected directly with said levers.
2. In brake structure of the class described, the combination of a stationary brake beam, a supporting beam alongside of said stationary brake beam, a brake beam movable on said supporting beam and extending parallel with said stationary beam, bearing frames rigidly mounted on said supporting beam, cylindrical cam disks on said frames for cooperating with said movable brake beam, shafts extending eccentrically from said disks and journaled in said bearing frames, levers

extending from said shafts, means for swinging said levers to simultaneously actuate said cam disks to shift said movable brake beam relative to said stationary brake beam, and means for bodily adjusting said supporting beam relative to said stationary brake beam. 70

3. In brake structure of the class described, the combination of a stationary brake beam, a supporting beam alongside of said stationary beam, a brake beam movable on said supporting beam toward and away from said stationary beam to vary the braking gap between said brake beams, bearing frames secured on said supporting beam, eccentric pressure members mounted on said frames and operating shafts extending therefrom and journaled in said frames, levers extending from said shafts, a common actuating rod for said levers, and bolts anchoring said supporting beam to said stationary beam by means of which said supporting beam may be adjusted relative to said stationary beam. 75 80 85

In witness whereof, I hereunto subscribe my name this 30th day of April, 1928.
